UNITED STATES PATENT OFFICE.

EGBERT O. DOAK, OF CANASTOTA, SOUTH DAKOTA.

GRAIN-CAR DOOR.

1,253,160.

Specification of Letters Patent.

Patented Jan. 8, 1918.

Application filed September 29, 1916. Serial No. 122,905.

To all whom it may concern:

Be it known that I, EGBERT O. DOAK, a citizen of the United States, residing at Canastota, in the county of McCook and State of South Dakota, have invented new and useful Improvements in Grain-Car Doors, of which the following is a specification.

This invention relates to improvements in grain car doors and has particular application to a combined swinging and sliding door.

In carrying out the present invention, it is my purpose to provide a grain car door which will be connected to the car in such manner that the same may be swung outwardly under the weight of the grain so that the door may be relieved of such weight and then moved along the wall of the car 20 out of the door opening, so that the grain or other material may be discharged from the car freely.

It is also my purpose to provide a grain car door which may be moved across the door opening and then locked against the wall of the car to effectively close the door opening so as to prevent leakage of the grain through the opening after the grain or other material has been delivered to the car.

Another object of my invention is the provision of a car door wherein the upper portion of the door will be formed of relatively movable sections capable of swinging movement to open position, so that the grain, coal, or other material may be delivered to the car through the upper end of the door, after the door has been locked as a unit at closed position, the upper sections of the door permitting the contents of the car to be inspected, whenever necessary or desired, without loss of any of the material in the car.

With the above and other objects in view, the invention consists in the construction, combination, and arrangement of parts hereinafter set forth and falling within the scope of the claim.

In the accompanying drawings:—

Figure 1 is a fragmentary side elevation 50 of a car equipped with a door constructed in accordance with the present invention.

Fig. 2 is a vertical sectional view showing the door in closed position.

Fig. 3 is a similar view showing the door 55 swung outwardly and ready for sliding movement to open position.

Fig. 4 is an enlarged cross sectional view through a portion of the upper end of the door and the frame therefor.

Fig. 5 is a horizontal sectional view on 60 the line 5—5 of Fig. 1.

Fig. 6 is an enlarged cross sectional view through the lower portion of the door frame, showing the means for latching the door in closed position.

Referring now to the drawings in detail, A designates a car of suitable construction provided with the usual doorway B. The lintel of the doorway B is preferably reinforced by angle bars 1, while secured to the 70 outer side of the wall of the car contiguous to the edges of the doorway and surrounding the latter is a metal frame C, having the inner edges of the side and end bars thereof formed with outwardly projecting 75 flanges c. Fastened to the inner surface of the side wall of the car contiguous to the upper end of the door opening is one leg of an angle plate 2, and the other leg of the angle plate 2 projects through the door 80 opening immediately below the upper edge thereof, and fastened to the upper surface of the last mentioned leg of the angle plate is a track bar 3, of a length greater than the width of the door opening and projecting 85 beyond the respective side edges of said opening. The outer edge of the track plate 3 is formed with a depending flange 4.

In the present instance, the door of the car embodies a substantially rectangular 90 frame E of a height and width to close the door opening and adapted to fit between the flanges c when the door is in closed position. Mounted in the frame E and suitably fastened therein is a bottom section 5 terminating short of the upper end of the frame, and hinged to the upper edge of the bottom section 5 is a movable section 6 capable of outward swinging movement, while hinged to the upper end bar of the frame E is a section 7 capable of inward swinging movement

and coöperating with the section 6 to close the space between the upper end bar of the frame and the top edge of the bottom stationary section 5 of the door. Fastened to 100 the upper end bar of the frame E adjacent to the respective ends of such bar are elongated straps 9 arranged transversely of the top bar of the frame E. 10—10 designate hangers, each embodying a plate 11 having 105 the upper end formed to provide bearings 11' in which are journaled the ends of an

axle carrying a roller 13 bearing upon the track plate 3. The lower end of each plate 11 is formed to provide an upwardly extending flange 12 spaced apart from the 5 plate and arranged upon the side of the frame 4 opposite from the plate so that the hanger will be held against outward movement on the track plate. The lower end of the plate of each hanger is also formed with 10 depending bearings 12', in which are journaled the ends of a shaft 13' that extends through the strap 9, the strap being arranged between the bearings 12', as clearly illustrated in Fig. 1 of the drawings. By 15 means of the elongated straps 9, it will be seen that the door may be swung bodily away from the car so that the door may be relieved of the weight of the contents of the car, and after the door has been so relieved 20 it may be moved longitudinally along the track plate 3 to uncover the door opening, thereby permitting the contents of the car to be freely discharged, the roller 13 and the hangers 10—10 sliding over the track 25 plate 3 in the sliding of the door, and the flange 12 engaging the flange 4 to hold the hangers against outward movement on the track plate. Thus accidental removal of the door from the car is prevented.

30 In the present embodiment of my invention, the locking mechanism for the door embodies a king plate 14' preferably mounted upon a pin carried by the bottom section 5 of the door in the center of such section. 35 Connected to the king plate 14' at diametrically opposite sides of the pivot pin 15 are the inner ends of links 16, and the outer ends of the links 16 terminate short of the respective side edges of the door. Secured 40 to the lower section 5 of the door adjacent the respective corners thereof are lock casings 20, each having the outer wall formed with a slot 22 and slidably mounted within the respective lock casings 20 are bolts 19 45 adapted to be projected through the alining slots in the side bars of the frame E and in the flanges c when the door is in closed position. These bolts act to hold the door up against the side wall of the car so as to 50 effectively close the door opening and prevent leakage of the contents of the car through the door opening. Connected to the bolts 19 and projecting outwardly through the slots 22 are pins 20' respectively, and connected to the pins 20' upon 55 each side of the door are the outer ends of vertical levers 17, the levers being fulcrumed between their ends within brackets 18 secured to the lower section of the door. The 60 inner ends of the lever 17 upon each side of the door are pivotally connected to the adjacent end of the corresponding link 16. The king plate 14' is equipped with a sliding lever 14 and connected to the outer end 65 of the king plate 14' is one end of a draw

bar 24 slidably mounted in a bearing bracket 25 and having the other end thereof equipped with a handle 26 whereby the draw bar may be manipulated. The draw bar 24 is formed with an opening that alines with 70 openings in the bearing bracket 25 when the draw bar is actuated to project the bolts 19, and through these alining openings is passed a hand pin 27 to hold the bolts in projecting position. By means of this construction, it 75 will be seen that when the door is moved across the door opening and disposed between the flanges c, the draw bar 24 may be actuated to swing the lever 14 and the plate 14', thereby transmitting a swinging movement to the lever 14 through the medium of the links 16 so that the locking bolts 19 will be projected through the slots or openings, thereby locking the door in closed position. 80

The section 6 of the door is equipped with 85 bolt casings 32, respectively, adjacent to the side edges thereof, and slidably mounted within these casings are bolts 31 having their outer edges adapted to engage keepers 33 carried by the side bars of the frame E. 90 The inner ends of the bolts 31 are connected with the outer extremities of links 30, respectively, and the inner extremities of the links 30 are pivotally connected to ears 29 formed on a lever 28 fulcrumed between its 95 ends upon a pin 28' carried by the section 6 of the door. Thus it will be seen that when the lever 28 is swung in one direction motion will be transmitted through the links 30 to the bolts 31 to project the latter into 100 the keepers 33 thereby locking the section 6 of the door in closed position. On the other hand, when the direction of movement of the lever 28 is reversed the bolts are withdrawn and the section 6 of the door may be 105 swung into open position. In the present instance, the upper end of the lever 28 is equipped with an outwardly projecting keeper 34 adapted to be engaged by one end of a bolt 35 slidably carried within a bracket 110 36 carried by the section 7 of the door. Thus, when the bolt 35 is engaged with the keeper 34, the lever 28 is locked against movement to hold the bolts 31 in engagement with the respective keepers, and as 115 the bracket 36 is carried by the section 7 and lever 28 carried by the section 6, the section 7 of the door is held in closed position.

In order to check the outward swinging 120 movement of the door when the latter is relieved of the influence of the bolts 19, I employ the following mechanism:

Connected to the outer wall of the car below the door and adjacent to the side edges 125 of the latter is an arm 37 projecting outwardly from the car and having the outer end bifurcated as at 38, and pivoted within the bifurcated end of the arm 37 is a lever 39 having the upper end normally disposed 130

in the path of movement of the door and the lower end connected with a spring 41 that acts upon the lever 39 to resist an outward movement of the door. The upper 5 end of the lever 39 is preferably beveled outwardly as at 40. The upper ends of these levers 39 engage the lower edge of the door when the car is empty and the door across the door opening and unlocked thereby preventing 10 swinging of the door in the travel of the car. On the other hand, when the car is loaded and the door unlocked to release the contents of the car the lower edge of the door swings beyond the lever 39 under 15 the weight of the grain or other material, thereby permitting such material to be discharged from the car, the door being moved along the track plate out of the door opening and the outward swinging of the door. 20 It will be understood that previously to unlocking the door the stop 39 will be manually moved to carry the upper end 40 out of the path of the door. It should further be noted that the lever 39 is of such dimensions 25 and so pivoted relatively to the door, and the door itself is so proportioned, that the bottom portions of the door will engage against the stop 39 when in operative position regardless of whether strap 9 is inwardly or outwardly disposed on the shaft 13'.

While I have herein shown and described the preferred form of my invention by way

of illustration, I wish it to be understood that I do not limit or confine myself to the 35 precise details of construction herein described and delineated, as modification and variation may be made within the scope of the claim and without departing from the spirit of the invention.

40 I claim:—

The combination with a car having a door opening therein, of a track plate arranged above the door opening and connected to the car, hangers carried by said track plate and 45 capable of longitudinal movement thereon, a door adapted to close said door opening, connections between said door and said hangers whereby the door may be swung outwardly from the wall of the car and subsequently moved along the track plate to completely uncover the door opening, and means for limiting the outward movement 50 of the door, said means comprising a plurality of outwardly extending arms attached 55 to said car below said door opening, a retaining member pivotally attached to each arm and having one end normally disposed in the path of movement of said door, and means for limiting an outward movement 60 of such end of said member, said last mentioned means adapted to permit unrestricted inward movement of such end of said member.

In testimony whereof I affix my signature. 65
EGBERT O. DOAK.
